HOLDER FOR A BEVERAGE BOTTLE

Harold Brandeis, Skokie, Ill.

Application April 3, 1956, Serial No. 40,882

Term of patent 7 years

(Cl. D58—26)

Fig. 1.

Fig. 2.

Fig. 1 is a front elevational view of a holder for a beverage bottle showing my new design; and
Fig. 2 is a top plan view thereof.

The rear and sides of the holder not shown are similar to the front panel shown in Fig. 1, except for the surface ornamentation shown on the front panel and identified by the dotted lines.

The dominant features of my design reside in the portions shown in full lines.

I claim:

The ornamental design for a holder for a beverage bottle, substantially as shown and described.
